Winifred Davis, Los Angeles, Calif.

Application December 18, 1950, Serial No. 13,493

Term of patent 14 years

(Cl. D44—25)

To all whom it may concern:

Be it known that I, Winifred Davis, a citizen of the United States, and a resident of the city of Los Angeles, in the county of Los Angeles and State of California, have invented a new, original, and ornamental Design for a Sectionalized Teapot, of which the following is a specification, reference being had to the accompanying drawings, forming part thereof, in which:

Fig. 1 is a top plan view of a sectionalized teapot showing my new design;

Fig. 2 is a side elevational view; and

Fig. 3 is a front elevational view thereof.

I claim:

The ornamental design for a sectionalized teapot, as shown.

WINIFRED DAVIS.
